UNITED STATES PATENT OFFICE

143,258

DESIGN FOR AN INTERMEDIATE BEARING AND BEARING RETAINER FOR ROTATING SHAFTS POSITIONED IN A COLUMN

Leonard Aker, Atherton, Calif., assignor, by mesne
assignments, to Fairbanks, Morse & Co., a cor-
poration of Illinois

Application July 24, 1944, Serial No. 114,537

Term of patent 14 years

(Cl. D46—1)

To all whom it may concern:

Be it known that I, Leonard Aker, a citizen of the United States, residing at Atherton, in the county of San Mateo and State of California, have invented a new, original, and ornamental Design for Intermediate Bearing and Bearing Retainer for Rotating Shafts Positioned in a Column, of which the following is a specification, reference being had to the accompanying drawing, forming a part thereof.

Fig. 1 is a front elevational view of an intermediate bearing and bearing retainer for rotating shafts positioned in a column embodying my new design;

Fig. 2 is a top plan view thereof.

I claim:

The ornamental design for an intermediate bearing and bearing retainer for rotating shafts positioned in a column, as shown.

LEONARD AKER.
